UNITED STATES PATENT OFFICE.

GEORGE R. HENDERSON, OF ROANOKE, VIRGINIA.

RELIEF MECHANISM FOR PISTON-VALVES.

SPECIFICATION forming part of Letters Patent No. 655,080, dated July 31, 1900.

Application filed January 11, 1899. Serial No. 701,839. (No model.)

To all whom it may concern:

Be it known that I, GEORGE R. HENDERSON, a citizen of the United States, and a resident of Roanoke, Virginia, have invented certain 5 Improvements in Relief Mechanism for Piston-Valves, of which the following is a specification.

The object of my invention is to provide means for automatically relieving the piston- 10 valve of a locomotive or other engine of excessive back pressure, due to compression of water or steam in the cylinder of the engine of the locomotive.

Piston-valves, owing to the nature of their 15 construction, are not able to relieve themselves the same as a slide or **D** valve. The slide-valve will be raised from its seat by the excessive back pressure in the cylinder, thus relieving the pressure. Safety-valves have 20 been provided on the cylinder-heads for the purpose of relieving back pressure in the locomotive using a piston - valve, but these safety-valves have proved unsatisfactory.

In the accompanying drawings, Figure 1 is 25 a sectional view through one cylinder and valve on the line 1 1, Fig. 3. Fig. 2 is a section on the line 2 2, Fig. 3. Fig. 3 is a sectional plan view on the line 3 3, Fig. 1; and Fig. 4 is an enlarged sectional view of a portion of Fig. 2, illustrating more clearly my 30 invention.

In the drawings I have shown simply one cylinder-casting of a locomotive of the ordinary piston-valve type. The cylinder-casting 35 on the opposite side will be a duplicate of the one shown.

A is the cylinder-casting, having the cylinder **B**, the valve-chamber **C**, and the steam-inlet passage **a** and passages **b**, one communicating with one end of the cylinder and the other with the opposite end. **c** is the exhaust-passage communicating with the ports at each end of the valve-casing.

I have omitted the piston and its rod as well 45 as the valve, as these parts form no part of my present invention and are of the construction ordinarily used in this type of engine.

Steam is admitted from the boiler through the central live-steam passage **a** to a passage 50 **b** and into one end of the cylinder, while the steam is exhausting from the opposite end of

the cylinder through the other passage **b** to the exhaust-passage **c**, and when the valve is moved into the opposite position the passage of the steam and exhaust are reversed.

55

In the cylinder-casting **A** are two partitions **A'**, forming a cavity **a'** directly under each passage **b**, communicating with the cylinder. Screwed into the partition is a valve-seat **d**, and adapted to the seat is a check-valve **D**. 60 When the valve is opened, the passage **b** communicates with the passage **a** through the cavity **a'**; but the check-valve is on the under side of the partition, and consequently will close with pressure in the live-steam passage 65 **a**, so that the valve is normally closed when the throttle-valve of the engine is opened; but when the locomotive is standing and the live-steam passage **a** is free of steam under pressure the valve **D** will drop from its seat 70 and allow the passage **b** to communicate with the passage **a**.

When the throttle-valve is open, steam will be admitted from the boiler into the passage 75 **a**, and as the cavities **a'** communicate with the passage the two valves **D** will immediately close and will remain closed as the pressure in the cylinder-passage **b** is normally less than that in the live-steam passage **a**. If, however, the pressure in either one of the 80 passages **b** should be increased either by undue compression or by water in the cylinder above the steam-pressure in the passage **a**, the valve **D** will be forced from its seat and the pressure in the passage **b** will be instantly relieved, thus preventing breaking or damaging 85 the cylinder-head or piston.

While the above is the main feature of my invention and the point which the invention is intended primarily to cover, yet it affords 90 the advantage of allowing the locomotive to drift without creating a vacuum in the steam-chest. When steam is cut off, both check-valves **D** will remain open and the air can be forced from one end of the cylinder to the 95 other through the valves. Further, this construction will prevent locomotives from starting owing to the leaky throttle, as the steam as it slowly escapes will pass around the valves **D** and into the passage **b** to the exhaust-passage **c**.

Referring to Fig. 4, directly under the valve

is a screw-cap d' . On removing this screw-cap the valve and the valve-seat can be removed.

While I prefer to place the valves in the 5 particular position shown, they can be placed at any point in the partition between the live-steam passage a and the cylinder-passages b , as in some types of engines it may not be convenient to place the valves in the position 10 shown in the drawings. If the valve is placed in the horizontal position or reverse from that shown in the drawings, a light spring may be used to force the valve off its seat when pressure in the live-steam passage a is reduced.

15 It will be understood that while I have shown a locomotive with a central steam-supply passage and end exhaust-passages this invention can be attached to an engine having end steam-passages and a central exhaust 20 without departing from the main feature of my invention.

I claim as my invention—

1. The combination of a cylinder, a cylindrical valve-casing, a central steam-inlet passage, side cylinder-passages and end exhaust-passages, cavities extending from the live-steam passage under the cylinder-passages, ports in the partition between the cavities and the cylinder-passages, a check-valve in 30 each port normally open but closing against steam-pressure in the live-steam passage and opening against said steam-pressure when there is excessive back pressure in one or other of the cylinder-passages, substantially 35 as described.

2. The combination in a locomotive, of a

steam-cylinder, a cylindrical valve-chest, live-steam and exhaust passages leading to said valve-chest and ports leading to the steam-cylinder, a chamber to one side and below said valve-chest communicating with the live-steam passages, two check-valves in the partition between the said chamber and the steam-ports of the cylinder, said valves being normally held open by gravity, substantially 45 as described.

3. The combination in a locomotive-cylinder casting, of a steam-cylinder, a cylindrical valve-chest, passages leading from said valve-chest to the steam-cylinder, to the exhaust 50 and to the live-steam supply, a partition forming with the walls of the cylinder a chamber communicating with the live-steam passages, and check-valves with valve-seats in said partition opening into the passages to the steam-cylinder, threaded openings in the lower wall 55 of said chamber directly beneath the check-valves through which both valves and seats may be introduced and fitted in place and threaded plugs constructed to close said openings, said valves and threaded openings being inside of the locomotive-frame and so placed as to be readily accessible, substantially as described.

In testimony whereof I have signed my 65 name to this specification in the presence of two subscribing witnesses.

GEORGE R. HENDERSON.
